UNITED STATES PATENT OFFICE.

EDWARD J. BROOKS, OF EAST ORANGE, NEW JERSEY, ASSIGNOR TO THE
E. J. BROOKS & COMPANY, OF NEW YORK, N. Y.

DESIGN FOR A SEAL PART FOR SEALS.

SPECIFICATION forming part of Design No. 28,343, dated March 8, 1898.

Application filed June 23, 1897. Serial No. 641,990. Term of patent 14 years.

To all whom it may concern:

Be it known that I, EDWARD J. BROOKS, a citizen of the United States of America, and a resident of East Orange, in the State of New Jersey, have invented and produced a new, useful, and original Design for a Seal Part for Seals, of which the following is a specification.

The nature of the design is illustrated by a sheet of drawings which accompanies this specification as part thereof.

Figure 1 of the drawings is a face view of the seal part, showing the new design; and Figs. 2 and 3 are views of the respective lateral edges of said seal part.

The shape or configuration of said seal part comprises a quadrangular general outline, as shown in Fig. 1, a pair of projections 1 on the face of the seal part, presenting the appear-

ance of a diagonal bar, and a hollow quiver-shaped diagonal projection 2, crossing the line of said projections 1 in the foreground and open at its larger end, as shown in Fig. 2, the outer ends of said projections 1 and the ends of said projection 2 partaking of the angles of the quadrangular outline. Four substantially triangular depressions 3 at the face of the seal part complete its leading and material features.

Having thus described said design, I claim as new and original and desire to patent under this specification—

The design for a seal part substantially as shown and described.

EDWARD J. BROOKS.
